L. D. SMITH

SURGICAL SYRINGE

Filed May 25, 1925

INVENTOR:

Lemuel D. Smith

BY Allen & Allen

ATTORNEYS.

UNITED STATES PATENT OFFICE.

LEMUEL D. SMITH, OF MILWAUKEE, WISCONSIN.

SURGICAL SYRINGE.

Application filed May 25, 1925. Serial No. 32,599.

My invention relates to surgical syringes in general and particularly to surgical syringes such as may be used for infiltration, blood transfusion, and aspiration.

5 It is the object of my invention to provide a syringe for such uses which will be simple in construction and easily sterilized; which will create an even flow without variation in pressure and which will have a valve construction not liable to stoppage. It is further my object to provide a syringe with reversible discharge and suction elements permitting a wide variety of uses. It is 10 further my object to construct a syringe which may be continuously used as required in some surgical treatments without the necessity of recharging.

The only type of infiltration syringe now 20 on the market is dependent on a suction and a pressure stroke for each injection and does not offer any possibility of continued use such as would be preferable in the treatment of a comparatively large area of tissue with novocaine, or the like. Further all infiltration 25 syringes now in use have small valves in the end of the syringe casing which frequently stop up and consequently subject the physician to innumerable delays and the consequent risks to the health of the patient.

30 The usual type of aspirating syringe is dependent on the operation of small valves to control the suction and discharge which clog up and have a tendency to cause back pressure on the reverse stroke with the risk to the patient incident with such back pressure. For blood transfusion work is exceedingly important that the operation be conducted quickly and accurately and that the 35 blood be transfused before it coagulates. Heretofore the usual type of blood transfusion apparatus has either consisted in apparatus requiring a treatment of the blood 40 to prevent coagulation, because of the length of time required to operate the apparatus, or it has depended for its operation on the transfer of the blood from one cylinder to another or the manipulating of valve control handles.

45 In a syringe made in accordance with my invention it is my object to provide ease of operation, positiveness of action, and such even regulation of pressures within the syringe that results in all of the aforementioned

treatments, hitherto impossible, may be accomplished.

55 Referring to the drawings:

Figure 1 represents a side elevation of a preferred type of syringe.

Figure 2 is a cross section longitudinally 60 through the syringe illustrated in Figure 1.

Figure 3 is a detail section showing a ball valve modification of the conical poppet valve construction.

Generally indicated at 1 is the graduated cylinder forming the side walls of the suction and compression chamber which may be made of glass, as indicated or metal depending on the particular requirements of its use. A plunger rod 2 with a handle 3 moves longitudinally through the cylinder. 70 Each end of the cylinder is provided with flanges 4 preferably of metal which are secured to the glass by compression or the use of cementitious material. The flange at the plunger end is provided with a projecting pin 5 which engages a spiral slot 6 in a cap 7 which fits over the flange and secures to the cylinder the head member 8 which fits within the cylinder and has an integral sleeve 9 extended away from the cylinder. This 75 sleeve is machined preferably to a sliding fit about the plunger rod so that there will be no necessity of providing a packing box which would be difficult to sterilize properly.

80 The plunger rod has a piston head 10 secured to the end and it is disposed within a sliding valve 11 of equivalent diameter as that of the inner side of the cylinder. The valve has a ground face 12 with which the piston head engages when the plunger 90 is pulled back. The valve is hollow as indicated at 13 and a peripheral groove 14 in the end opposed to the piston engagement end is adapted to abut a spider 15 or other projection secured to the plunger rod. 95

A modification illustrated in Figure 3 is 100 preferable from the point of view of manufacturing cost. In this modification the piston head 10 is supported on the end of the rod 2 by curved spider arms 15^a and a ball 15^b retained between the spider and the piston head seats in a concentric beveled face 15^c in the piston head.

105 The operation of the syringe will be at once apparent. Pulling the plunger handle away from the cylinder will result in draw-

ing in liquid into the cylinder through an opening in the bottom flange. After the cylinder is filled a reverse stroke of the plunger handle will result in the piston 5 plunger moving inwardly enough to clear the opening in the valve, and the valve being forced down with the piston when the spider on the plunger rod abuts the groove in the valve. The liquid which has thus 10 been transferred from one side of the valve to the other will be discharged from the cylinder through an aperture 17 in the head enclosing the plunger end of the syringe.

The operation of the syringe, after the 13 first charge has been drawn in, may be carried on indefinitely and with the large aperture in the valve it will further be apparent that there will be no tendency to create back pressure.

20 To reverse the action of the syringe all that is necessary is to use the tubes which are preferably attached to the ends of the flanges in reversed position. A further modification of the syringe illustrated is to 25 provide a piston head which has instead of a spider on the plunger side of the valve a spider on the other side of the valve so that the movement of the plunger into the cylinder will force liquid out through the aperture on the end opposite the plunger. This 30 modification is preferable for some uses as the hand in moving the plunger inwardly has a tendency to move more evenly than when pulling out on the plunger and for 35 uses requiring a very even discharge the latter arrangement is less subject to variation.

Various modification of structure will occur to those skilled in the art without departing from the constructive principle 40 involved.

Having thus described my invention, what I claim as new and desire to secure by Letters Patent, is:

1. In a surgical syringe, a hollow cylinder and a plunger rod with means for retaining the plunger rod slidably within the cylinder and a hollow member adapted to slide within the cylinder and to form a compression tight joint between its outer walls 45 and the inner walls of the cylinder, and the rod adapted to retain the member and a valve element adapted to form a compression tight joint with the member with movement of the rod in one direction, and to be retained with a loose joint with movement in the opposite direction with a valveless opening in one end of the cylinder adapted to act as an inlet suction and a valveless opening in the other end adapted to act as a discharge from the cylinder.

2. In a surgical syringe, a hollow cylinder and a plunger rod with means for retaining the plunger rod slidably within the cylinder, and a hollow member adapted to slide 65 within the cylinder and to form a compression tight joint between its outer walls and the inner walls of the cylinder, a valve element, and the rod adapted to seat said element against the member with movement of 70 a rod in one direction, and to carry the element with a loose joint with movement in the opposite direction, with a valveless opening in one end of the cylinder adapted to act as an inlet suction and a valveless 75 opening in the other end adapted to act as a discharge from the cylinder and one of the ends of the cylinder adapted to be removably connected whereby the plunger rod and the valve may be withdrawn from the cylinder.

LEMUEL D. SMITH.
